UNITED STATES PATENT OFFICE.

JESSE D. BABB, OF DALLAS, GEORGIA.

SASH-LOCK.

1,102,710.

Specification of Letters Patent.

Patented July 7, 1914.

Application filed August 30, 1913. Serial No. 787,436.

To all whom it may concern:

Be it known that I, JESSE D. BABB, a citizen of the United States, residing at Dallas, in the county of Paulding and State of Georgia, have invented certain new and useful Improvements in Sash-Locks, of which the following is a specification, reference being had to the accompanying drawings.

10 This invention relates to new and useful improvements in sash locks and more particularly to a spring-actuated window sash lock, the object of the invention being to provide a lock of this character whereby a 15 window sash can be raised or lowered and securely locked in any desired position and will also be effectually prevented from rattling.

Another object of the invention is to provide 20 a sash lock which will possess advantages in points of efficiency and durability, is inexpensive of manufacture and, at the same time, is simple in construction and operation.

25 With the above and other objects in view, the invention consists in the novel features of construction and the combination and arrangement of parts hereinafter more fully described, pointed out in the claim and 30 shown in the accompanying drawings, in which,

Figure 1 is a front elevation of a window frame constructed in accordance with my invention, illustrating the application of my 35 improved sash lock. Fig. 2 is a side elevation of the sash lock. Fig. 3 is an end elevation. Fig. 4 is a longitudinal section of the same taken upon the outer side of the lever. Fig. 5 is a similar view taken upon 40 the inner side of the lever. Fig. 6 is a transverse sectional view.

Referring more particularly to the drawings, 1 indicates the window casing and 2 and 3 the upper and lower sections of the 45 sash which are slidably mounted therein. Secured to the window casing and to the front face of the upper sash, are the metallic strips 4 and 4', each strip being provided with a plurality of notches 5 which are 50 adapted to receive the locking bolt 6 and the operating lever 7 of the sash lock 8.

My improved sash lock 8 comprises an 55 elongated casing 9 having an enlarged portion 10 at one end provided with an inwardly extending notch 11. The casing 9 is preferably open at both ends and is pro-

vided upon its longitudinal edges with the outstanding flanges 12 which are provided with suitable openings whereby the same may be secured, by means of screws or the like, to the upper end of the lower sash 3 at one side thereof. The locking bolt 6, which is slidably mounted within the casing 9 and adapted for normal engagement with the notches in the strip 4, is provided with 60 an elongated slot 13 and is further provided with the outstanding lug 14, upon one face thereof. This lug 14 is adapted to be engaged by a second lug 15 formed on the pivoted operated lever 7, so that upon 65 the actuation of the lever, the bolt 6 will be reciprocated within the casing 9. The operating lever 7 is pivotally mounted upon a transverse pin 16 which extends entirely through the casing 9. Mounted upon the 70 pin 16 and arranged within one end of the slot 13 is a nut 17 which is adapted to bear against one end of the coil spring 18 when the locking bolt is released from the notches in the strip 4, placing the spring under tension, whereby the tension of the spring will 75 turn the locking bolt to its normal or locking position. The inner end of the operating lever 7 is provided with a tapering portion 19 which, when the lever is in its 80 normal position bears against the one wall of the casing so that the locking bolt will not retract farther than is needed to securely lock the sash.

As illustrated in Fig. 1, the strips 4 and 4' 90 are so arranged that the notches in the strip 4 are so arranged to receive the end of the locking bolt, while the strip 4' is arranged so that the notches will receive the curved end portion of the operating lever 7, thus 95 securely holding either of the sashes against movement. The outer end of the operating lever is provided with an opening in which is engaged one end of a cord 20, the other end of said cord extending downwardly 100 through an eye 21 to the lower end of the window casing so that it will be within easy reach to operate the lock.

From the above description, it will be readily apparent that I have provided a 105 simple and durable sash lock which can be quickly and readily applied to a window sash and which is easily operated and is effective in its operation. It will be seen that the device as a whole is extremely 110 simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claim.

Having thus described this invention, 10 what is claimed is:—

A device of the class described including notched strips secured to the upper sash and casing of a window, a lock including a casing secured to the lower sash, a spring actuated locking bolt slidably mounted therein 15 and normally engaging the strip on the sash, a lug carried by said locking bolt, a piv-

oted operated lever, a hook carried by the operating lever and adapted to engage the lug on the bolt to actuate said bolt, said lever having its outer end normally engaging the strip on the casing and its inner end provided with a tapering portion adapted to bear against one wall of the casing to limit the retarding movement of the locking bolt, and means secured to said lever whereby to actuate the locking bolt and release the sash for movement.

In testimony whereof I hereunto affix my signature in the presence of two witnesses. 20

JESSE D. BABB.
